ARTICLE SECURING PIN

Fred Kaufman, Bloomington, Ill.

Application November 17, 1932
Serial No. 643,083

1 Claim. (Cl. 24—156)

The present invention relates generically to novel and simple, but highly efficient, attaching or retaining means. More specifically, this invention has particular relation to an improved 5 form of securing means of the safety pin type especially adapted for use by launderers, cleaners, tailors, ready-made clothing manufacturers and others.

Cleaners often find that in many cases the 10 buttons of garments to be cleaned or otherwise handled are about to become detached, and probably would be lost during the cleaning process or other treatment unless means is taken to securely retain the button in place. This may, of course, be effected by sewing but this is a relatively time-consuming, and consequently expensive, expedient, particularly if the batch of garments to be cleaned comprises a large number of loosely attached buttons. The desirability and 20 utility of simple and inexpensive means which will enable one to quickly and securely retain the button in place during the cleaning or like operation is therefore apparent. Upon return of the suits to the tailor, the aforesaid means will direct 25 his attention to the loose character of the attachment of the button, which may then be properly sewed into its place.

The present invention has for its principal object the provision of button attaching or securing 30 means possessing the several characteristics above-described. Briefly, the preferred embodiment of the invention for effecting the functions outlined consists of a safety pin which is provided with a pin section of greater length than 35 is usual in pins of this type, and which pin section is deformed to provide, in association with the conventional tread-carrying section of the pin, a configuration substantially like that of an isosceles triangle. The shorter leg of the deformed pin section constitutes the base of the 40 triangle, and the longer leg extends, when the pin is closed, at an acute angle from this base to the head. A pin of this construction thus provides a pin portion which may be inserted 45 through a hole in the loose button of any of the customary types and then passed through the garment to prevent the button from being detached and lost, the aforesaid base member providing means which extends through the button 50 without producing bending or torsional stresses tending to twist or break the button.

Tailors and ready-made clothing manufacturers very often secure an extra button to the inside of a garment by sewing thereon. Substitution of the improved pin, in accordance with

the present invention, for the sewing would represent a substantial saving in time and expense.

Pins constructed in accordance with the invention may also find use in department stores, stationery stores, hardware stores, etc., as they 60 may be employed to hold a large group of articles, such as papers, materials, etc., together.

The pins may also be produced in varying sizes, ranging from a very small size to a large size depending upon the use to which they are to be 65 put.

The foregoing and other objects, which will be apparent to those skilled in the art to which the present invention pertains from the detailed disclosure thereof hereinafter set forth, are attained by the construction and novel combination and arrangement of parts fully described below, illustrated in the accompanying drawing and pointed out in the claim hereunto appended.

In the said drawing,—

Fig. 1 is a view of a preferred embodiment of a safety pin constructed in accordance with this invention; and

Fig. 2 is a view illustrating the method of utilizing the pin, shown in Fig. 1, to securely retain 80 a button on a garment or the like, a portion only of the latter being shown.

Corresponding reference characters designate similar parts throughout the several figures of drawing.

Referring now to the drawing, and more particularly to Fig. 1 thereof, it will be seen that reference numeral 10 designates, as a whole, one preferred construction of pin according to the invention. Pin 10 may preferably comprise a 90 head-carrying section 11 and a pin section 12, connected at their juxtaposed ends by means of a spring loop 13, such as is more or less conventional in the usual safety pin construction. The several portions 11 and 12, as well as the intermediate spring loop 13, may conveniently be fabricated from a single length of wire of suitable metal.

The pin section 12 is made substantially longer than the head-carrying section 11, and preferably comprises a relatively short leg 14 approximately in length three times the width of the head 16, as shown and a relatively long leg 15. The head-carrying section 11 is provided at its free end with a head or clasp member 16 of suitable construction, wherein the free or pin point end of leg 15 is adapted to be retained when the pin is in closed position.

The short leg 14 preferably extends approximately at right angles to the head carrying sec- 110

tion 11 when the pin is open, as shown in Figure 1, and at an acute angle to the head-carrying section 11, in the closed position of the pin as shown in Figure 2 on the drawing, and the long leg 15 extends from the short leg to the clasp 16, defining an acute angle with each of the head-carrying portions 11 and the short leg 14. The head-carrying section 11 and the two legs 14 and 15 thus constitute a pin body which is of the configuration, substantially, of an isosceles triangle.

The short leg or base 14 of this triangle, as is particularly evident from Fig. 2, provides a convenient shank portion upon which the button 17, to be securely retained on the garment 18, may be handily disposed, and which provides free accommodation for the button 17 without exposing it to twisting or torsional forces tending to break it, as would be the case with a pin portion extending directly, and without deformation, to the 20 clasp from the spring loop.

The pin portion of the pin 10 may readily be inserted through a hole of a loosely-attached button 17 (see Fig. 2) and then passed through the garment 18 to secure the button from being lost 25 during treatment of the garment.

It will be apparent from the foregoing detailed description of an embodiment of this invention that a novel and simple, but efficient and inexpensive, means is thus provided for effecting the 30 desired objects.

While a preferred form of the invention has been illustrated and described, it will be understood that a number of modifications and variations may be resorted to without departing from

the spirit of the invention. For example, the length of the base 14 may be varied to accommodate a plurality of buttons, as where a clothing manufacturer desires to provide several spare buttons, or to accommodate buttons of different or considerable thickness; any other suitable type of head member or clasp 16 may be utilized in place of the form illustrated; etc. The preferred disclosure is therefore to be regarded as illustrative and the scope of the invention is not to be limited thereby or otherwise than by the terms of the following claims.

What is claimed is:

A button securing safety pin, formed of resilient wire having a head secured at one end thereof, said wire coiled to form a spring intermediate its length, the wire extending from the spring towards the head in one direction to provide a head carrying section and in another direction at approximately right angles to the head carrying section for a distance approximately three times the greatest dimension across the width of the head to form an intermediate section and then bent in the direction of the head to provide a pin carrying section, the free end being pointed and adapted to be engaged and protected by the head whereby the intermediate section separates the wire into the contiguous head and pin sections to cause said sections, when the pointed end is in engagement in the head, to form an isosceles triangle therewith and affords a button engaging portion when the pin is engaged in the fabric.
